UNITED STATES PATENT OFFICE.

HENRY H. DENT, OF FULLERTON, PENNSYLVANIA.

DESIGN FOR A LOCK-CASE.

SPECIFICATION forming part of Design No. 24,310, dated May 14, 1895.

Application filed March 2, 1895. Serial No. 540,387. Term of patent 3½ years.

To all whom it may concern:

Be it known that I, HENRY H. DENT, a citizen of the United States, residing at Fullerton, in the county of Lehigh and State of Pennsylvania, have invented and produced a new and original Design for a Lock-Case, of which the following is a specification, reference being had to the accompanying drawings, forming part hereof, in which—

10 Figure 1 is a front elevational view of a lock-case, illustrating the shape and form of my design. Fig. 2 is a sectional view thereof; and Fig. 3 is an edge view, these three views being deemed necessary in order to fully illustrate the lock-case constituting the shape and form of my design.

The leading feature of my design consists of a lock case, comprising the ornamental face with the raised ornament and the rim or border with raised surface ornamentalizations or conventionalized grotesque animal shapes in conjunction with leaf, scroll and bead or scale ornaments, the outlines of which when viewed in elevation, as in Fig. 1, fall within the outlines of the lock case and are symmetrically disposed with relation to the face of the case.

Referring to the drawings A, is the rectangular face of the case in which is situated the key-hole.

20 B and B', are the upper and lower rims or borders respectively surmounting and depending from the face A. These rims or borders are irregular in contour, conforming to the outline of the raised ornaments on the 35 surface of the rims.

The face A, is ornamented with the raised leaf and stem ornamentalizations C, raised scroll ornaments D, represented as intertwined with the leaves, and two fields of raised irregularly 40 shaped circular ornaments E. This face is further provided with the raised ornament F, the face of which has artistic scroll ornaments D'.

The face of the upper border or rim B, is 45 ornamented with raised crescent-shaped orna-

ments G, representing conventionally a portion of the body and head of a winged grotesque animal, as a dragon, surmounting the face A. The rim or border B, is further ornamented on one edge with a raised conventional shield ornament H, representing the wings of a grotesque animal, and on the other edge with a combined raised spiral ornament J, and forked ornament K, representing conventionally the coiled body, tail and hind 50 claw of the animal.

The surface of the border B, within the crescent is ornamented with a raised conventional claw-shaped ornament L, and a raised scroll-shaped ornament M, representing respectively the conventional form of the claw of the grotesque animal, grasping the spiral or scroll of leaves.

The surface of the border B, is further ornamented at the corners with the conventional ivy-leaf ornament N.

The surfaces of the border B, and of the face of the case A, are further ornamented by a spiral row of bead or scale-like ornaments O.

The surface of the lower depending border B', is ornamented with a corresponding raised crescent-shaped ornament G', a shield ornament H', a spiral ornament J', a fork ornament K', a claw-shaped ornament L', a leaf scroll ornament M', ivy leaf ornaments N', and 75 bead or scale ornaments O'. In the lower border B', these ornaments are reversely arranged with relation to the corresponding ornaments of the border B.

What I claim is—

80 The design for a lock-case, substantially as shown and described.

In testimony whereof I have hereunto set my signature in the presence of two subscribing witnesses.

HENRY H. DENT.
